UNITED STATES PATENT OFFICE.

DANIEL J. MURNANE, OF CHICAGO HEIGHTS, ILLINOIS, ASSIGNOR TO ZOURI DRAWN METALS COMPANY, OF CHICAGO HEIGHTS, ILLINOIS, A CORPORATION OF ILLINOIS.

FRAMING CONSTRUCTION.

1,300,757.

Specification of Letters Patent. Patented Apr. 15, 1919.

Application filed October 29, 1917. Serial No. 199,095.

To all whom it may concern:

Be it known that I, DANIEL J. MURNANE, a citizen of the United States, residing at Chicago Heights, in the county of Cook and 5 State of Illinois, have invented a new and useful Improvement in Framing Construction, of which the following is a specification.

My invention relates more particularly to 10 improvements in framing construction, the members of which are built into place on the job, my invention having been devised more particularly for embodiment in the door-framing portions of show cases, such as are 15 oftentimes used in the entrance-ways of stores and employing hinged doors.

In the building of such framing structures, it is customary for the workman to set up the side framing members and the top 20 and bottom framing members and rigidly fasten them together to form the opening into which the door, or other closure, is to be inserted, but it often happens that in constructing the framing some of the members 25 are set incorrectly, providing a door-opening less, or greater, than the desired width, or height, necessitating in the former instance, the widening of the opening. This operation, where the frame members are of wood, 30 is relatively expensive and should be avoided if possible, as it involves carpentry work on the frame or door, after the latter has been set, but in case the framing members are entirely of metal, or inclosed in a metal 35 sheathing, the expense and difficulty of correcting the errors in erecting, are multiplied many times.

My object is to provide improvements in 40 framing construction to the end that the necessity for the same degree of accuracy in assembling the main members of the frame, as is the case with structures as hitherto provided, to effect the proper fit of the door within the frame in an opening, is 45 overcome, and whereby a door-opening of the desired size may be provided without entailing the relatively great inconvenience and cost which oftentimes results from the building of framing structures as now commonly provided, where any of these framing members are improperly set, particularly if of metal or metal sheathed.

Referring to the accompanying drawings,

Figure 1 is a broken view in elevation of the door equipped portion of a show case of 55 the general character above referred to, the framing for the door being constructed in accordance with my invention. Fig. 2 is a view in sectional elevation of the structure shown in Fig. 1, and partly broken away, 60 the section being taken intermediate the side members of the door. Fig. 3 is a broken plan sectional view taken through the door portion shown in Fig. 1; and Fig. 4 is a perspective view of a portion of a strip 65 forming a size-regulating strip, employed in connection with the main members forming the door frame and which is provided as a member separately settable from the main frame members to insure the proper fit 70 of the door in the door frame.

As my present invention relates primarily to the formation of the framing forming the door-opening of the show case, I shall limit the description to this portion 75 of the structure. It may be said, however, that the part represented at 5 is the lower section of the show case, the upper portion 6 of which forms the lower member of the framing in which the opening 7, for the 80 hinged door 8, is provided. The member 6 is formed of the sill member 9 supported on a rail 10 with a stop cleat 11 secured to the rear portion of the upper side of the sill member 9, the front exposed surfaces of 85 these three members being covered by the metal strips 12, 13, and 14, respectively, in accordance with common practice.

The door opening 7 is formed between a corner bar 15 and a division bar 16 which 90 rise from the member 6, as shown in Fig. 1, and are secured thereto in any suitable manner, these bars reaching up preferably to the top of the case where they are connected with the top rails (not shown) of the case 95 in any suitable manner. These bars in the particular arrangement illustrated are formed of wood, sheet-metal covered as represented at 50, though it is to be understood that the invention may also be practised by 100 forming these bars of wood only or of metal either of solid or hollow construction. The corner bar 15 is equipped with clamping means represented at 17 which serve to clamp the adjacent pane 18 of glass, to this 105 bar, this pane resting against a seat 19 pro-

vided along the outer surface of the bar 15. The clamping means shown comprise a right-angled molding strip 20 which fits over the outer corner of the bar 15 as shown and is clamped against the pane 18 through the medium of a bar 21 located within the member 20 and held in clamping engagement with the member 20 through the medium of bolts 22 provided at intervals along the bar 15. The bar 16 which carries a stop cleat 23 at the door-opening 7 presents a seat 24 for the adjacent pane 25, of glass, which is clamped in place through the medium of clamping mechanism 26 of the same general construction as clamping mechanism 17. In the particular construction illustrated the door, represented generally at 27 is hinged to the bar 16 as through the medium of the hinges indicated at 28.

20 The top member of the framing forming the door-opening 7 is represented at 29, this member being in the form of a bar extending between the bars 15 and 16 and secured thereto in any suitable manner, with a stop cleat 30 at the rear portion of its underside and a seat 31 for the lower edge of the pane 32 of glass which extends above the door-opening. The pane 32 is shown as clamped in place against the member 29 through the medium of clamping mechanism 33 carried by the bar 29^a and of the same construction as the clamping mechanism 26.

30 Provided preferably in connection with both the bar 15 and the bar 29 are size-regulating strips 34 preferably of metal and of Z-shape as shown, which are formed separately from these bars and are provided for assembly therewith to extend to adjacent edges of the door 27, and become to all intents and purposes and to all appearances a part of the door framing, by the adjustment of which, the frame-work is caused to conform to the size of the door. The strip 34 which extends along the inner side of the bar 15 throughout the height of the door-opening, lies at its rear flange 35 against a seat 36 on the bar 15 and extending generally parallel with the plane in which the door-opening extends, and at its forward flange 37 against a seat 38 provided on the outer face of the bar 15, the portion 39 of the bar 34 thereby extending into the recessed portion 40 of this bar and being held in place therein by any suitable means securing the strip 34 to the bar 15 as, for example, by the brads 41 and 42 which pass through the flanges 35 and 37 and into the bar 15, the clamping means 17 extending over the flange 37 sufficiently far to cover the brads 42 and 60 make a tight joint with this flange.

As will be seen the securing of the Z-shaped size regulating strips 34 in place through the end flanges prevents distortion from lateral strain of the comparatively thin metal from 65 which said strips are formed.

The strip 34 at the top of the door-opening and coöperating with the bar 29^a seats at its flanges 35 and 36 against the outer face of the stop cleat 30 and the outer face of the bar 29, with its portion 39 extending into the recessed portion 43 of this top-bar, the strip 34 being secured in place by any desirable means, such as the brads shown at 44 and 45.

In the building of the structure the main members of the door framing are assembled 75 with the other parts of the frame members of the structure and secured together, the members of the door framing at one side and at the top, represented in the particular construction shown, by the members 15 and 29, 80 being set in the building of the frame structure as stated, to provide a door-opening of greater width and height than the door 8, when the structure is built according to the preferred embodiment of my invention. 85 The door 8 is then hung upon the hinges 28, and then the strips 34 are applied to the members 15 and 29 to the positions hereinbefore stated, and are adjusted on the bars 15 and 29 to produce an opening to conform 90 to the size of the door, in which position these strips 34 are secured as by the brads 41, 42, 44 and 45.

While it is preferred that both the upper and one side member of the door framing be 95 constructed with a separately formed strip, such as that indicated at 34, it will be understood that the invention may be embodied in a structure wherein this adjustable strip feature is provided along one member only of 100 the frame, though such an arrangement does not present, in practice, all of the advantages of the preferred construction described.

The value of constructing framing as described will be manifest, inasmuch as the 105 same accuracy in setting the main framing members, as in the case of constructions as now commonly provided, is not necessary, because of the provision of the separate members which are set after the door is in 110 place, to cause the opening in the frame to conform to the size of the door.

While I have illustrated and described a particular construction in which my invention is embodied, I do not wish to be understood as intending to limit it thereto as the same may be variously modified and altered without departing from the spirit of my invention, it being my intention to claim my invention as fully and completely as the 120 prior state of the art will permit.

What I claim as new and desire to secure by Letters Patent, is:—

A framing construction forming a door-opening, one of the members thereof being 125 formed of a section connected with the adjacent framing members and having a recessed portion with front and rear seats facing in substantially the same direction and arranged at opposite sides of said recess, and a 130

second, size-regulating strip section of substantially Z-shape in cross-section bearing at its lateral portions against said seats and extending at its intermediate portion in said 5 recess, and adapted to cause the door-opening to conform to the size of the door and means securing said second section to said

first-named section in said position at both of said seats, said second section being adapted to be secured in said position after 10 said first-named section has been secured in place.

DANIEL J. MURNANE.
